APPARATUS FOR HANDLING RADIOACTIVE SOLUTIONS

Waverly Q. Smith and George W. Struthers, Oak Ridge, Tenn., assignors to the United States of America as represented by the United States Atomic Energy Commission

Application September 5, 1944, Serial No. 552,810

7 Claims. (Cl. 23—259)

1

This invention relates to an apparatus and method for handling radioactive solutions. More particularly, this invention concerns an apparatus and method for handling samples of radioactive solutions used in connection with analytical or similar work.

In certain types of processes now carried out, there are obtained large quantities of radioactive solutions. In the operation of such processes it is desirable from time to time to withdraw various amounts of solution to provide samples used for analytical and control purposes in connection with the operation of said processes. However, even small samples, namely samples comprising a few cubic centimeters or less exhibit vigorous activity. The activity of these small samples may be such that they must be kept out of contact with the person and preferably maintained at some distance therefrom. In addition, the samples are of sufficient activity that in the handling thereof, it would be undesirable for drops to fall upon floors, laboratory benches, or the like because of the contamination which this would cause.

In view of the active nature of the above solutions, conventional methods and apparatus used in handling ordinary chemical liquids are not satisfactory for handling those solutions. It is therefore apparent that the development of a suitable apparatus and method whereby radioactive solutions may be conveniently handled with a minimum of danger from spillage or other difficulties represents a highly desirable result.

We have discovered a novel apparatus and method for the utilization of the apparatus that is particularly suitable for handling solutions exhibiting a high degree of radioactivity wherein the solutions may be handled at a distance from the person and handled with a minimum of danger from breakage and spillage. It is further apparent that since our apparatus may be employed in handling solutions having a very high degree of activity that the apparatus may also be used for handling solutions of lower activity. Also, our apparatus may find use in handling ordinary chemical liquids.

This invention has for one object to provide an apparatus and method for handling radioactive solutions.

Another object is to provide an apparatus that is particularly suitable for handling samples of solutions having a very high degree of radioactivity.

Still another object is to provide an apparatus for handling active solutions of the class described, particularly samples thereof that are used for analytical or other laboratory or control purposes.

Still another object is to provide a pipette

2

construction for handling samples of radioactive solutions wherein after the pipette has been filled, there is a minimum of danger of spillage therefrom during the movement and handling of the filled pipette.

Another object is to provide an apparatus for handling active solutions of the class described wherein the solutions may be filled and discharged under protected reduced pressure conditions.

Still another object is to provide an apparatus for handling radioactive solutions of the type described wherein the portion of the apparatus containing the solution may be handled and moved at a distance from the person.

A still further object is to provide an apparatus of the type referred to for handling active solutions which is simple and inexpensive in construction and may be made from readily obtainable materials.

A still further object is to provide novel methods for handling samples of radioactive solutions under protected conditions including filling the sampling device and discharging the sampling device into a receiver.

Other objects will appear hereinafter.

We have found that a suitable device for handling radioactive solutions comprises a specially designed pipette together with a holder therefor and a receiver for the solution. A demountable handle construction may be provided for moving certain of the parts of the apparatus and means may be provided for filling and discharging the pipette under protected reduced pressure conditions.

For further understanding of our invention, reference is made to the attached drawings forming a part of the present application.

Fig. 1 is a perspective view of the entire construction showing the apparatus generally in an opened condition.

Fig. 2 is a detail view of the pipette construction.

Fig. 3 is a side elevation view showing in general the apparatus in a closed condition. That is, the parts which are shown in Fig. 1 in a removed position are shown in place in Fig. 4.

Fig. 4 is a sectional view taken on line A—A of Fig. 3 in which certain of the parts have been shown broken away for a better understanding of the interior construction of the apparatus.

Referring to Fig. 1, 2 represents the overall carrier type container for the sample receiver and other glassware or similar parts. This container 55 2 may be constructed from wood, plastic, or other suitable material as will be described. It is provided with a drawer-like member 3 adapted to be inserted in one of the sides of container 2. Provision is made, as for example in the block member 4, for inserting a receiver tube 5. The

active sample of solution is ultimately collected in this tube receiver. Clamp means of standard construction are provided at 6 for securely holding tube 5. The clamp 6 has an outer reduced screw threaded end which passes through the forward wall of the drawer 3 and is drawn up by a wing or thumb nut until the shoulder at the juncture of the reduced portion tightly engages the inner face of the forward wall. This serves to mount the clamp 6 on the drawer 3. The opposite end of the clamp is ring shaped and expandable as indicated in Fig. 1. It receives and supports tube or receiver 5 in position.

Referring further to container 2, clamp means 7 are also provided for securely holding the sheath member 8 (to be described in detail in connection with Fig. 4) within the container. The clamp 7, indicated in Fig. 1, is similar to clamp 6, described in detail above, and is mounted in the container 2 through its outer reduced extension which passes through an opening in the cross member bridging the front and rear walls of the container. It is held in place by the usual wing nut threaded upon the reduced extension. An opening 9 is provided in the container 2 for permitting access to the aforementioned clamp and the reduced pressure inlet 10. A detachable handle means 11 is provided for holding container 2 at a distance when active materials are in the apparatus. Also, a similar provision is made with respect to drawer 3, namely screw heads 18 are provided so that the demountable handle may be attached for moving and holding drawer 3 when containing a tube of active solution. In this connection, it will be seen in Figs. 1, 3 and 4 that handle 11 terminates at its forward extremity in a flat vertically extending plate having spaced grooves or recesses formed in its upper edge. These grooves or recesses are adapted to receive the body portions of the screws on the container 2 or the screws 18, 18 of the drawer 3. These screws, when tightened down engage the plate on handle 11 through their heads and lock it to the container 2 or the drawer 3 as the case may be.

Referring to Fig. 2, reference numeral 12 denotes a sampling pipette. This pipette is similar to a standard laboratory type pipette, and is provided with a tapered tip at 13. However, this pipette is sealed off at 14 at which point there is attached a long handle member 15 so that the hand may be kept away from the liquid in the pipette. A stopper or comparable closure means is provided at 16 which is adapted to fit into member 8 as will be described under Fig. 4.

Referring to Fig. 3, this view shows drawer 3 and the pipette in place. The other parts are as has been indicated.

Referring to Fig. 4 which is a sectional view shown on line A—A of Fig. 3, there is shown the pipette 12 inserted into member 8. The pipette, when so inserted, may be discharged by applying reduced pressure at conduit 10 (Fig. 1). The pipette discharges from tip 13 into sample tube 5. The sheath member 8 merely comprises an elongated tube, tapered at the lower end so that it may be inserted into sample tube 5 in a reasonably secure manner. This is desired so that reduced pressure may be applied without substantial leakage. Also spillage of the solution is avoided during discharge of the pipette. While the use of a stopper 19 has been indicated, and constitutes a simple and an inexpensive means for securing the sheath into tube 5, other means such as a ground joint may also be used. The sheath, the tube, and the pipette may be con-

structed of glass, stainless steel or the various plastics. The preferred material would be a non-breakable, transparent substance which permits visual observation.

The apparatus of the present invention is particularly suitable for use in connection with removing a sample from a quantity of solution adapted to be placed under reduced pressure. That is, in sampling solutions from a larger container a portion of the solution in the container would be pumped, as by reduced pressure or other means, through an external circuit in order that a homogeneous portion of the liquid be obtained. Otherwise, if a sample were taken from the surface liquid, it might not be representative of the remainder of the liquid in the container being sampled.

Our device, namely the pipette construction shown in Fig. 2, is adapted to be inserted into a reduced pressure atmosphere through a suitable opening into an external circuit as above mentioned, the stopper 16 closing off the opening. The reduced pressure evacuates the interior of pipette 12 after which it is immersed in the liquid to be sampled. Upon restoring the pressure to atmospheric, with the tip 13 of the pipette immersed in the liquid to be sampled, the liquid flows into the pipette. This permits the filling of pipette 12 until it is full or until it is pulled out of the liquid. Upon breaking the vacuum, the liquid which has entered pipette 12 is retained therein by atmospheric pressure without danger of spillage. By means of the long handle 15, it is possible to keep the hand at a safe distance from the solution contained in the pipette. The pipette may be carried to the laboratory or otherwise handled until it is desired to discharge the liquid therefrom.

In order to discharge the pipette the container 2 is assembled, and the parts securely clamped as shown in Fig. 4 so that sample tube 5 is beneath sheath 8. The pipette 12 is inserted into the top of member 8. Reduced pressure is applied to conduit 10 and this causes the liquid in the pipette to flow out at tip 13 into the sample tube 5. The pipette should not be inserted so low in member 8 that tip 13 becomes immersed in the discharged liquid.

Thereafter member 8 may be raised and drawer 3 containing tube 5 removed by means of handle 11 and carried, or otherwise handled without material danger of spillage or other difficulties, for analytical or similar work.

After removing drawer 3, another drawer of the same type containing a tube similar to tube 5 filled with cleaning solution may be inserted and the apparatus reassembled. By applying the reduced pressure at 10 and immersing the pipette into the cleaning liquid followed by restoration of atmospheric pressure and then a reversal of the operations, the pipette may be cleaned. That is, it may be observed that the pipette 12 will be filled when the reduced pressure is broken while the tip 13 is in the cleaning liquid. The liquid forced into the pipette 12 is held there by atmospheric pressure. Consequently, the pipette may be moved and handled without material danger of liquid escaping from tip 13. Removal of the liquid from pipette 12 requires the application of reduced pressure at 10 with the tip 13 positioned above tube 5. The cleaning fluid is thereby caused to flow out of pipette 12 into receiver tube 5. Alternate filling and discharging, as aforementioned, may be accomplished until the pipette is cleaned.

In the present arrangement it will be noted that the discharging and filling, since they are carried out by the application of reduced pressure with the pipette inclosed, eliminates the possibility of spattering or other contamination of the person or materiel. Protection may be obtained by making the container 2 and other of the parts from materials which shield against radioactivity. That is, the container may be lined with lead or other conventional shielding material or plastics having shielding material molded therein may be employed. Similar remarks apply to the construction of the pipette 12, the sheath 8 and similar parts of material exhibiting a shielding effect such as leaded glass or certain plastics.

It is to be understood that all matters contained in the above description and examples are illustrative only and do not limit the scope of this invention, as it is intended to claim the invention as broadly as possible in view of the prior art.

We claim:

1. An apparatus for handling radioactive solutions comprising a container, a pipette receiving sheath disposed within said container, a removable drawer positioned in the container and adapted to mount a receiver in communication with said sheath, and means for supporting said sheath in position in said container.

2. An apparatus for handling radioactive solutions comprising a container, a pipette receiving sheath positioned within the container, said sheath comprising an elongated tube having an inlet conduit associated therewith whereby a source of reduced pressure may be applied to the sheath for altering the contents of a pipette, and a removable drawer positioned in the container in communication with said sheath, said drawer being adapted to hold a receiver for collecting the contents of the pipette.

3. An apparatus of the class described comprising a container, a sheath disposed within the container, and a removable drawer positioned in the container beneath the sheath and adapted to mount a receiver in communication with said sheath.

4. An apparatus of the class described comprising a container, a pipette receiving sheath member positioned within the container, said sheath being secured to the container, means for reducing the pressure within the sheath to discharge the pipette, and a drawer providing a receptacle for a removable receiver positioned below and in communication with said sheath for reception of liquids from said pipette.

5. An apparatus for handling radioactive solutions comprising a container, sheath means positioned within the container including an elongated tube having an inlet conduit for communication with a pressure source, said sheath means being adapted to receive the discharge end of a closed pipette, and a removable holder positioned in the container, said holder being adapted to carry a receiver for communication with the sheath to receive liquids discharged from the pipette.

gated tube having an inlet conduit for communication with a pressure source, said sheath means being adapted to receive the discharge end of a closed pipette, and a removable holder positioned in the container, said holder being adapted to carry a receiver for communication with the sheath to receive liquids discharged from the pipette.

6. An apparatus of the class described comprising a container, sheath means for the reception of a pipette positioned within the container, a removable drawer member in the container for communication with said sheath and a removable handle member secured to the container for transporting it.

7. An apparatus for handling radioactive solutions comprising a container, a sheath positioned in said container, a pipette adapted to contain radioactive solutions comprising an elongated tube tapered at one end, said tube being closed at the opposite end, a relatively long handled member attached to the closed end of the tube, a stopper encircling the pipette in the vicinity of the junction of the tube and handle member, said stopper being adapted to fit into the sheath, a removable drawer positioned in the container and adapted to hold a receiver in communication with said sheath, and means for altering the pressure within the sheath to discharge the pipette into said receiver.
